UNITED STATES PATENT OFFICE.

PHILIP H. FIELDING, OF NEW YORK, N. Y.

APPLIANCE FOR WIRING CONDUITS.

No. 895,175.

Specification of Letters Patent. Patented Aug. 4, 1908.

Application filed June 6, 1908. Serial No. 320,399.

To all whom it may concern:

Be it known that I, PHILIP H. FIELDING, a citizen of the United States, residing at the city of New York, in the county of New York and State of New York, have invented certain new and useful Improvements in Appliances for Wiring Conduits, of which the following is a full, clear, and exact description.

My invention relates to conduit wiring, and particularly to the provision of a convenient lamp receptacle or rosette adapted for use with wiring of this class.

The principal object of the invention is to provide a form of receptacle which can be fixed directly upon the ordinary metal piping of a conduit system, and in which the electric connections are made in a simple, convenient and highly efficient way, and so as to hold the circuit wires of the conduit firmly in a fixed relation out of contact with the conduit walls.

A further object of the invention is to enable the parts to be quickly assembled into place, to have them firmly locked or held in place when properly positioned, and to attain perfect insulation of all electrical connections by having them completely incased in porcelain channels or ducts through which the circuit wires are led at the points of connection.

Finally I aim to provide a practical structure of pleasing appearance which has few parts, and which is not liable to breakage or disorder.

With these and other objects in view, my invention consists in the features of construction and combination hereinafter set forth, and particularly as pointed out in the appended claims.

In the drawings: Figure 1 is a side view showing a conduit receptacle embodying the principles of my invention; Fig. 2 is a sectional view of the same; Fig. 3 is a top view with the lamp socket removed; Fig. 4 is a transverse sectional view on the line IV--IV of Fig. 3; Fig. 5 is a transverse section of the lamp socket; Fig. 6 is a perspective view of the circuit wires and parts, the conduit pipe being removed; Fig. 7 is an end view of the two parts of the receptacle in normal relation.

In conduit wiring for incandescent lamps, all the circuit wires are inclosed in metallic pipes, generally ordinary wrought iron pipe of convenient size. In order to make the necessary connections with the lamps, it is

necessary to cut and thread or aperture the pipe at the desired points in order to get access to the circuit wires. When the pipe is cut in this way the exposed wires must be prevented from short circuiting upon one another, or from grounding upon the pipe. They should also be protected from coming in contact with any outside objects, and dampness. All of these objects are attained by my present invention, and in addition thereto I obtain a strong, compact and pleasing lamp socket rigidly fixed upon the conduit piping, and which can be easily assembled into position or taken apart.

In carrying out my invention I employ a receptacle having two insulating parts, conveniently of porcelain, one of which is received within the conduit pipe, and the other of which has ears by which it is screwed to the outside of the pipe. The inside block or part constitutes the terminal block by which the circuit connections are made. The outside insulating block or part constitutes a lamp socket, and has a threaded shell or other device adapted to receive an ordinary incandescent lamp. The arrangement is such that the central stud connection of the lamp socket is formed by a metallic clip upon the inside block, and entirely independent of the lamp socket part.

Referring now to the drawings in which like parts are designated by the same reference sign, 1 indicates an ordinary conduit pipe, and 2 and 3 are the usual circuit wires contained therein. The pipe has an aperture 4 cut therein at the location where it is desired to have a lamp. In the practice of my invention I make the aperture 4 of generally rectangular form, occupying a section of the pipe, with end surfaces 5, perpendicular to the axis of the pipe, and side edges 6, the faces of which are preferably cut in the same plane, as clearly shown in Figs. 4 and 5. The transverse extent of this aperture has a special relation to the inside block, for a purpose which will be hereinafter stated.

Inserted within the pipe through this aperture is the inside block 7, having a rounded exterior surface 8, corresponding to the internal wall of the pipe, and having a flat upper face or ledge 9, on which the terminal connections are made.

10 indicates a ridge or partition, which extends in a direction generally longitudinal of the block and of the piping along the center of the flat face 9. The arrangement is such

that a space is left for the circuit wires 2 and 3 on either side of the central rib or partition 10.

In practice the rib or partition 10 is not perfectly straight, but is deflected at its central portion, and has an integral protuberance 11, which extends upward and through the aperture 4. This protuberance is conveniently flattened or recessed on one side, 10 and constitutes a support for the central stud terminal of the socket.

The two terminals are secured in place upon the face 9 of the inside block 7, and in practice I make the central stud terminal 12 15 with an upwardly extending stem 13, upon the top of which is a cap 14, which overlies the upper surface of the protuberance 11. The stem 13 is conveniently opposite the flat or recessed face of the protuberance 11 above 20 mentioned.

15 indicates an ear which is turned up upon a portion of the terminal clip 12, and 16 designates a screw closely adjacent to the ear 15, and which serves to clamp one of the 25 circuit wires thereagainst. The other terminal clip 17 has a corresponding ear 18 and clamping screw 19, co-operating therewith.

20 indicates a tubular extension on the terminal clip 17, for a purpose which will 30 presently appear.

The lamp socket block is indicated at 21, and has ears 22 apertured for screws 23, by which the block is secured to the pipe 1.

24 designates the threaded shell cemented 35 or otherwise fastened into the block 21, and additionally held by mechanical fastening means. For this purpose I conveniently employ a screw 25, which passes through the shell 24, metallic washer 24', and finally 40 through block 21, and into a threaded bushing 26, projecting on the lower side of the lamp socket block. The purpose of washer 24' is to insure a good electric connection between the shell and screw. The position of 45 the threaded bushing 26 is in axial alignment with the tubular extension 20 of the clip 17. 27 indicates a split portion of this bushing which is adapted to be received in said tubular extension 20. An additional fastening 50 means is obtained by the fastener 28 passed through the block 21, and shell 24, and having its head 29 in a counterbored recess in the block so as to preclude any possibility of a short circuit with the terminal beneath.

55 The lamp socket block 21 has a central opening 30 co-axial with the shell 24, and its lower face is rounded to a curvature corresponding to the internal bore of the pipe, as shown at 31. The length of this rounded portion is equal to the length between the end surfaces 3 of the aperture 4, so that the socket block is closely received into said aperture in use. The position of the ears 22 upon the socket block is such as to secure and preserve 60 this relation.

The use and operation is as follows: If being desired to locate a receptacle at any given point on the conduit pipe, an aperture 4 is made of the form above described. The circuit wires 2 and 3 are then bared for a 70 short portion of their length at points which will come opposite the terminal clips 12 and 17. It is now merely necessary to insert the inside block 7 into place, which can be accomplished by an endwise movement. In 75 this relation the circuit wires 2 and 3 lie on opposite sides of the central rib 10, and opposite the terminal clips 12 and 17. The bared portions are now clamped against the ears 15 and 18 by simply tightening the respective screws 16 and 19. It will be observed that in this relation the two wires are adequately protected from one another by the central partition or rib 10, and they are protected from any contact with the conduit pipe by the two porcelain blocks which form between them a pair of ducts or channels which completely incase the bared portions. This protection is partly due to the shape of the lower surface 31 of the socket block which 80 takes the place of the pipe at all points where any short circuit might otherwise be possible. 85 This curved surface of the socket block 21 slightly overlaps the edges of the inside block 7 so as to give absolute protection. It is of course not essential to have this particular form of either block, the important characteristic being to have a pair of ducts or channels formed when the two blocks are placed together, in which the bared portions of the 90 wires are completely incased. The relation is clearly indicated in Figs. 6 and 7 from which it will be seen that the individual circuit wires have what are virtually little vitreous conduits at the region where they are 95 bared for the connections.

The socket block 21 is placed in position so that the protuberance 11 extends upward through the opening 30 therein, and the bushing 27 projects downwardly into the 100 tubular extension 20 of the other terminal socket establishing the electric connections and holding the two blocks firmly together. The screws 23 being then driven into place, the receptacle is complete and ready for use. 105

While the invention has been described more particularly in connection with a lamp receptacle, it is obvious that the features thereof are equally applicable to use in rosettes and all similar electric appliances which 110 are employed with conduit wiring. I do not therefore desire to be limited or restricted to the particular application shown.

What I claim, is:-

1. In combination with a conduit pipe 125 having a cut-out portion therein and having circuit wires, a block of a size corresponding to said cut-away portion of the conduit pipe and adapted to be placed therein beneath the circuit wires, an additional block positioned 130

outside of the conduit pipe and means on said additional block to make electrical connections with the inside block when positioned on the conduit pipe opposite said cut-away portion.

5. In combination with an ordinary cylindrical water-tight conduit pipe having a cut-away portion and circuit wires therein, two blocks of insulating material one of which is received within the conduit and has terminal clips on its upper face, said terminal clips being connected to the circuit wires and the other of which blocks projects through the conduit pipe to coöperate with the first named block to wholly inclose the circuit wires.

2. In combination with an ordinary cylindrical water-tight conduit pipe, two blocks of insulating material one of which is received 20 within the pipe and connected to the circuit wires therein, said circuit wires traversing the upper exposed face of the block, and the other of which projects through the conduit pipe, and electric connections from the circuit wires extending through said second block, said electrical connections being completed by positioning said second block in place.

3. In a lamp receptacle for wiring conduits, an inside block having an upper face with metallic clips thereon, a second block adapted to be positioned upon the first and coöperating therewith to form passages for the circuit wires, said passages being wholly 35 inclosed and continuous from one end of the block to the other, and means on said second block for establishing electrical connections from the circuit wires to an incandescent lamp.

40. 4. In a lamp receptacle for wiring conduits, an inside block having an upper face with metallic clips thereon, a second block adapted to be positioned upon the first and coöperating therewith to form passages for the circuit wires, said passages being wholly inclosed and continuous from one end of the block to the other, and means on said second block for establishing electrical connections from the circuit wires to an incandescent lamp.

5. In a lamp receptacle for wiring conduits, an inside block adapted to be inserted

within a conduit pipe and having a face which lies opposite the opening through which the block is inserted, said face adapted to support the circuit wires, and a second 45 block having a threaded shell positioned on the outside of the conduit and coöperating with said first named block to make electrical connections for an incandescent lamp.

6. In a lamp receptacle for wiring conduits, an inside block having a flat upper face and adapted to be positioned within the conduit pipe through an opening thereof, whereby such face is presented in exposed relation toward said opening and is adapted to support the circuit wires, a second block having a threaded shell and adapted to be positioned on the outside of the conduit pipe, and means whereby electrical connections are made for an incandescent lamp.

7. In a lamp receptacle for wiring conduits, an inside block having a flat upper face with metallic clips thereon, said clips having terminal screws, said block being formed to be inserted through an opening in the conduit pipe and to be positioned beneath the circuit wires with said face in exposed relation opposite said opening whereby the terminal screws may be tightened on the circuit wires from the exterior of the pipe, a second 65 block having a threaded shell having its under surface formed to be positioned on the exterior of the pipe, and means for making electrical connections for an incandescent lamp when said second block is placed in 70 such position.

In witness whereof, I subscribe my signature, in the presence of two witnesses.

PHILIP H. FIELDING.
